WIRE CLOTHESPIN

Allen L. Atkins, Chicago, Ill.

Application January 28, 1948, Serial No. 4,731

2 Claims. (Cl. 24—139)

1

This invention relates to clothes pins and more particularly to a clothes pin which is made out of metal wire and in which the two fingers or legs of the clothes pin are normally closed whereby same have to be spread against opposition offered to said spreading by the resilience of said legs in order to force the clothes pin onto a line, the pin having a rounded offset loop intermediate its ends wherein the line is adapted to be accommodated after having been moved thereto, and the pin being so constructed that when the line has reached the line loop, the arms can move towards one another thereby locking the line in the loop.

The principal object of the invention lies in the provision of novel means for fastening the loops of the clothes pin together. 15

Another object of the invention is to form a clothes pin out of a pair of loops nested one within the other and fastened together at one end thereof in a novel manner so that the opposite ends are free and resist spreading.

Still another object of the invention is to provide a novel end piece for holding the pin in assembly.

With the foregoing and other objects in view which will appear as the description proceeds, the invention consists of certain novel features of construction, arrangement and a combination of parts hereinafter fully described, illustrated in the accompanying drawings, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawings a preferred embodiment thereof, from an inspection of which, when considered in connection with the following description, my invention, its mode of construction, assembly and operation, and many of its advantages should be readily understood and appreciated.

Referring to the drawings in which the same characters of reference are employed to indicate corresponding or similar parts throughout the several figures of the drawings:

Fig. 1 is a perspective exploded view of a clothes pin embodying my new invention and showing the parts thereof prior to assembly.

Fig. 2 is a front elevational view of the clothes pin of Fig. 1 in assembled condition.

Fig. 3 is a side elevational view of the clothes pin of Fig. 2.

pin similar to that of Fig. 1, and in a manner in which same is associated with a clothes line.

2
Referring now to the figures, the reference character 10 refers generally to the preferred embodiment of my invention. Same is shown to consist of two looped legs 11 and 12 nested one within the other. For this purpose the looped leg 12 is of smaller diameter than the leg 11. These legs are formed of resilient wire and are arranged in the same plane by reason of their nesting as will be noted by reference to Fig. 3.

10 The legs 11 and 12 have their free ends rounded as shown at 14 and 15 and said rounded ends are bent away one from the other to thereby form a V-shaped entrance to the pin as shown at 16.

15 The opposite ends of each of the legs 11 and 12 are adapted to be permanently attached one to the other. For this purpose each is provided with squared abutting ends 17 and 18 respectively inwardly bent from their sides which preserves the necessary spacing of the loops. These ends 20 are fixed within an end piece 19 which ensheathes same and gives a neat appearance to the pin 10. The center of the end piece between the sides of the center loop is pinched together as shown at 20 and the top of the end piece is rounded over 25 the abutting ends 17 as at 21 whereby the end piece is rigidly and cleanly attached to the loops. The end piece is preferably formed of a section of flattened tubing as shown in Fig. 1 which is slipped over the assembled ends of the loops 11 and 12 and stamped into the formation just described. By this novel structure the operation 30 of forming the end piece 19 on the clothes pin 10 can be done in one stroke.

35 Each of the sides of the two legs 11 and 12, is provided intermediate its ends with a rounded loop or bight, all being at the same position along the pin. Said loops are shown at 22 and 23. The loops 22 on the leg 11 are bent from the sides in semi-circular formation in planes at right angles to the plane defined by the sides of the leg 11, and on the same side of the leg 11 as the bent end portion 14. Similarly the loops 23 are formed as semi-circular offset bends in the sides of the leg 12, in planes perpendicular to the plane of the 40 sides of the leg 12 and in the same direction as the bent portion 15.

45

The semi-circular loops 22 and 23 cooperate to form a substantially circular space 24 on each edge of the clothes pin 10, said spaces 24 being aligned for the accommodation therein of the clothes line.

The clothes pin is used in the conventional manner for clamping an article of cloth 25 to a clothes line 26. The operation of the device is as follows:

After the cloth member 25 has been draped on the line 26, the clothes pin 10 is grasped in the hand by pinching the end portion 19 between the fingers. This leaves the legs 11 and 12 free to bend. The clothes pin 10 is poised with the V-

shaped space 16 above the line 26, and moved downwardly so that the line 26 and cloth enter said V-shaped entrance space. The pressure upon the pin 10 causes the line 26 to spread the legs 12 and 11 one from the other in the directions in which the bent portions 14 and 15 extend. This movement is opposed by the resilience of the legs 11 and 12. As the line 26 passes the apex of the V-shaped entrance space 16 it enters between the sides of the legs 11 and 12 prior to entering the space 24. As the pin 10 is further pushed home, the line finally enters said space and, since the pressure upon the sides is partially relieved, the legs 11 and 12 partially close upon the line 26 and the cloth member 25 until the line loops 22 and 23 engage same. This confining action serves to substantially lock the clothes pin 10 upon the line 26 in a manner in which the clothes pin will not readily be removed other than by pulling same off the line.

The structure above described is such that the clothes are at no time subject to being pinched or torn by reason of shearing action between metal edges. The wire used may be of a non-corrosive type to keep the clothes and line clean.

It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. A clothes pin comprising a pair of legs fastened together at one end and each having diverging portions at the opposite end thereof, said legs being formed of nested elongated resilient wire loops each having two sides and adapted to spread when a clothes line is moved between said diverging portions and forced between said loops towards the fastened end, there being a space formed by the legs and intermediate the ends to accommodate the line and lock said pin there-

onto when said line has been moved along the legs between the loops to said space and thereinto, said fastened ends each being provided with squared abutting extensions bent at right angles from each side of each loop for maintaining the spacing between the sides of the respective loops, and a flat tubular member completely enclosing said abutting extensions of said loops on all sides thereof, said tubular member having a pinch closing off the same, and the inner end portion of the tubular member extending down the nested loops beyond the abutting extensions and having a pinch between the sides of the inner loop and adjacent the extensions of the inner loop.

15 2. An end fastening member for a wire clothespin which is formed of a pair of nested loops of wire fastened together at their open ends and free to spread at their closed ends, the fastening member adapted to be installed in one stroke of a crimping mechanism, the loops each having two wire sides, the fastened extremities of each side being bent at right angles inwardly towards its mate; said member comprising a flat tube engaged upon all of said inwardly bent extremities, 20 having rounded edges, a closed, smooth-jointed pinch on its outer end, and an inwardly deformed pinch upon its inner end, said latter pinch being disposed between the inner wire sides and adjacent said inwardly bent right angle extremities, 25 having rounded edges, a closed, smooth-jointed pinch on its outer end, and an inwardly deformed pinch upon its inner end, said latter pinch being disposed between the inner wire sides and adjacent said inwardly bent right angle extremities, 30 of said inner wire sides whereby said member completely confines all of said inwardly bent extremities.
